UNITED STATES PATENT OFFICE.

EDSON C. COVERT, OF CHICAGO, ILLINOIS, ASSIGNOR TO AMERICAN STEEL FOUNDRIES, OF NEW YORK, N. Y., A CORPORATION OF NEW JERSEY.

MACHINE FOR MOLDING.

1,027,595.

Specification of Letters Patent.

Patented May 28, 1912.

Application filed September 11, 1911. Serial No. 648,790.

To all whom it may concern:

Be it known that I, EDSON C. COVERT, a citizen of the United States, residing at Chicago, in the county of Cook and State of Illinois, have invented certain new and useful Improvements in Machines for Molding, of which the following is a specification.

My invention relates to the art of molding and has particular reference to semi-automatic means for handling flasks and pattern plates, supplying sand to the flasks, jolting the sand and finally reversing the flask and drawing the pattern.

In the manufacture of castings, the development during recent years has been along lines tending to increase production and lessen the cost thereof. This is accomplished by the use of automatic machinery whereby hand work is to a certain extent eliminated and by the arrangement of apparatus to the end that skilled labor may be partially if not entirely done away with.

In the machine of the present invention it is believed that hand labor is largely eliminated; that skilled labor is practically unnecessary and that the arrangement is such that the operations are continuous to the end that no time is wasted.

The machine here illustrated is intended particularly for use with flasks of medium size although by modifications it may be adapted for heavy flasks if desired.

My invention will be more readily understood by reference to the accompanying drawings, wherein—

Figure 1 is a side elevation of a molding machine constructed in accordance with my invention, and Fig. 2 is an end elevation of the same construction.

Referring more particularly to the drawings, it will be seen that on a suitable base I mount a stationary plunger 10, preferably hollow to lessen weight and provided with a conduit 11, by means of which fluid such as oil or water may be directed to the upper end thereof. Upon this plunger is mounted a cylinder 12, suitable packing or packing rings being provided in order to make a fluid-tight joint between the cylinder and the plunger 10. Preferably integral with

the cylinder 12 are two pairs of oppositely disposed radial arms 13, 14. Each pair of arms is provided with registering recesses 15, 16, within which the trunnions 17, 18, of metallic pattern plates 19, 20, are seated. 55 Projecting through openings in one of the arms of each pair are pins 21, 22, these pins acting as stops to hold the pattern plate in horizontal position. The pins may be so arranged as to seat within one of the openings 60 23, 24, formed in the pattern plate, in which case when it is desired to turn over the pattern and superposed flask, the pin is removed, the flask and plate allowed to turn, then the pin is inserted to hold the plate in 65 reversed position. It will be seen that the cylinder 12, together with its integral arms and the flasks carried by the arms may all be rotated on the plunger 10, the weight being supported by the fluid confined in the 70 cylinder and that such rotation may be easily performed by hand.

In order to supply sand to the flasks I prefer to employ the novel means shown, such means including two bins 25, 26. 75 Mounted below the bins are two measuring devices 27, 28, each measuring device being adapted to contain the requisite amount of backing and facing sand to fill a flask. These sand supplying devices are provided 80 with wheels 29, 30, which coöperate with tracks 31, 32, provided on the lower edges of the bins. On the lower edge of the measuring device 28 is a further track 33. To fill the measuring devices they are placed in 85 position of the full lines of Fig. 2 and the grating underneath the bins shifted to fill the measures. The measure 27 is then shifted by means of the wheels 29 onto the track 33, then both measures 27, 28, are 90 shifted to a point over a flask carried by one of the wheels 13, 14, the sand in the lower measure is then dumped, then the sand in the upper measure is dumped and allowed to pass through the lower measure. 95 I will not here describe the sand measuring devices more specifically inasmuch as this mechanism may form the subject matter of a separate application.

Secured to the bin 26 is a bracket 34, on 100

which is carried a fluid pressure cylinder 35. Within this cylinder is mounted a piston, to the stem 36 of which is connected by suitable chains 37, a grid 38, which is adapted to be lowered onto the sand contained in a flask, to assist in ramming or jolting the same. It has been found that during the jolting operation the sand is well packed at the bottom of the flask but that the top is shaken around and is loose. Therefore by the employment of a weighted cover the top is packed evenly with the lower portion. This packing is more satisfactorily accomplished by the use of a structure of the form 15 of a grid such as is shown. Directly underneath the grid is positioned a mechanical jolter 39, as shown in Fig. 1. A car 40, mounted on a track 41, is positioned on the side of the machine opposite to the jolter.

20 It will be seen that the cylinder and its connected parts are adapted to be raised and lowered on the plunger 10. In order that the jolter 39 may be automatically started and stopped, I provide a lever 43, attached 25 at 44 to a portion of the frame work. To this lever 43, is connected a rod 45, which operates the valve controlling the action of the jolter. It will be seen that the rod 43 has an inclined surface 46, which is adapted 30 to contact the flange 12^a of the cylinder 12.

The operation of my molding machine is as follows: Assuming the arms 13, 14, to be in the position shown in Fig. 1, a pattern plate is supplied to the arms 13 and held in 35 upright position by means of the pin 21. A flask 47 is supplied to the top of the pattern plate and the parts rotated until the flask is underneath the sand supplying means, as shown in dotted lines in Fig. 2. Sand is 40 supplied and the machine rotated further until the flask is located over the jarring machine 39. The fluid in the cylinder is then allowed to escape through the duct 11, and the flask deposited upon the jarring machine. As the cylinder descends the flange 12^a will contact the inclined surface 46 of the lever 43 and start the jarring machine into action. The grid is then lowered for 45 the requisite time. When the sand has been sufficiently jolted, the cylinder is raised and the flask picked up. Meanwhile another flask and pattern plate has been supplied to the then empty pair of arms 14. The machine is then rotated a quarter turn, sand is 50 supplied to the empty flask, and while the sand is being supplied, the pin 21 is removed and the flask and pattern plate allowed to turn bottom up. Rotation is then continued until the recently filled flask is 55 supplied to the empty flask, and while the sand is being supplied, the pin 21 is removed and the flask and pattern plate allowed to turn bottom up. Rotation is then continued until the recently filled flask is 60 over the jolter when the cylinder is allowed to descend. As the flask is deposited upon the jolter, the previously filled and jolted flask is lowered onto the car 40, as shown in dotted lines in Fig. 1, and while the jolting 65 action is taking place on the other flask, the

completed flask is disconnected from the pattern plate and removed by the car.

It will be seen that the operations described may be continued indefinitely and that there is no waste of time while the operations are being performed. It will be seen also that although I have shown but two radially projecting arms, that four or any other desired number might be employed. Furthermore, that different sand supplying devices might be used and that various other modifications might be made, all without departing from the spirit of my invention.

I claim:

1. A device of the class described, comprising, in combination, a rotatable and vertically movable carrier adapted for bodily vertical movement and rotation about a fixed axis, a plurality of pattern plates and flasks, each rotatably mounted on said carrier, means for supplying sand to said flasks, means for jolting said sand and means coöperating with said carrier for drawing the pattern, substantially as described.

2. A device of the class described comprising, in combination, a plunger, a carrier mounted on said plunger and adapted for vertical movement and rotation relative to said plunger, pattern plates and flasks mounted on said carrier, means for holding said pattern plates and flasks in horizontal position, means for supplying sand to said flasks, means for jolting the sand in said flasks and means for drawing the pattern, substantially as described.

3. A molding machine comprising, in combination, a stationary plunger, a cylinder coöperating with said plunger, a plurality of carrier arms connected to said cylinder, pattern plates and flasks mounted on said carriers, means for holding said pattern plates and flasks in horizontal position, means for supplying sand to said flasks, means for jolting the sand and means for drawing the pattern, substantially as described.

4. A molding machine comprising, in combination, a stationary plunger, a cylinder coöperating with said plunger, a plurality of carrier arms connected to said cylinder, pattern plates and flasks mounted on said carriers, means for holding said pattern plates and flasks in horizontal position, means for supplying sand to said flasks, means for jolting the sand, automatic means for starting and stopping said jolter and means for drawing the pattern, substantially as described.

5. A molding machine comprising, in combination, a plunger, a cylinder mounted on said plunger and adapted for rotation and vertical movement with relation thereto, a plurality of pairs of carriers projecting

radially from said cylinder, means on said carrier adapted to receive the trunnions of pattern plates, flasks carried by said pattern plates, means for supplying sand to said flasks, means for jolting said sand, automatic means for starting and stopping said jolter and means for drawing said pattern and removing said flask, substantially as described.
